COMBINED DRIP BAFFLE AND HANDLE FOR
REFRIGERATOR CLOSURESOthel I. De Graw, Greenville, Mich., assignor to
Gibson Refrigerator Company, Greenville,
Mich., a corporation of Michigan

Application July 15, 1948, Serial No. 38,913

2 Claims. (Cl. 62—103)

1

This invention relates to refrigerators, and more particularly to handles for auxiliary closures for refrigerators.

In some modern refrigerators provision is made for dividing the interior thereof into compartments in such a way as to permit only a limited circulation of air between the compartments. In that way, different temperatures are maintained in the various portions of the food storage chamber.

The present invention is intended primarily for use with such a refrigerator in which an evaporator compartment and a chilling compartment therebelow are closed at the front by individual auxiliary closures. The auxiliary closures are located between the main refrigerator door and the evaporator and chilling compartments. Frequently the upper of the auxiliary closures becomes so coated with moisture that it drips from the upper auxiliary closure onto the lower auxiliary closure, as well as onto the contents of the refrigerator, without falling into the usual drip pan.

The principal object of the present invention is to provide a novel and ornamental handle for at least the lower auxiliary closure that will act as a deflector to convey moisture dripping from the upper auxiliary closure into a drip pan.

Another object of the invention is to provide a handle that will serve to conceal the gap which is formed between the evaporator and drip pan and which is usually quite evident in refrigerators of this type.

These objects, as well as others ancillary thereto, will appear in the following specification when read in connection with the accompanying drawings, wherein:

Figure 1 is a front elevational view of a refrigerator embodying the present invention, the main door of the refrigerator having been removed in order to more clearly show the interior of the refrigerator;

Figure 2 is a fragmentary cross-sectional view taken on substantially the line 2—2 of Figure 1; and

Figure 3 is a fragmentary cross-sectional view taken on substantially the line 2—2 of Figure 1 but showing only a smaller portion of the refrigerator on a larger scale, and illustrating the drip pan mounted in a position different from that in Figure 2.

The principal parts of the refrigerator to which the present invention is adapted are more fully disclosed in the copending application of Homer

2

E. Rosebrook, Serial No. 38,899, filed July 15, 1948.

In general, the refrigerator comprises an insulated cabinet 10 having therein a refrigerated food storage chamber 11. The chamber 11 is provided with a large access opening closed by an insulated door 12.

An evaporator 13 for cooling the interior of the food storage chamber 11 is mounted in the latter adjacent the top thereof. The evaporator 13 preferably is of generally rectangular box-shaped form of any well known construction, and is open at the front. Preferably the evaporator 13 extends substantially from front to rear and from side to side of the food storage chamber 11.

Below the evaporator are a plurality of shelves 14 and 15. The shelves 15 may be of any suitable type, either of open grid construction or of imperforate form. The shelf 14, however, is an imperforate plate, preferably of glass, which forms a partition between the spaces thereabove and therebelow.

The shelf 14 is spaced slightly from all of the upright sides of the cabinet, permitting a restricted flow of air between the space above the shelf and the space below it.

Between the door 12 and the shelf 14 and the evaporator 13 are two auxiliary closures 16 and 16a. Preferably the closures are formed of glass. They are hingedly connected at their lower edges on horizontal axes to the sides of the refrigerator cabinet. The closures 16 and 16a are positioned close to but not quite touching the evaporator 13 and the shelf 14. The closures act to restrict the flow of air between the spaces above and below the shelf 14, as well as to assist in preventing entrance of heat to the space above the shelf 14 when the door 12 is open.

A drip pan 17 normally is positioned below and in relatively close proximity to the evaporator 13, as shown in full lines in Figure 2. This drip pan is a shallow pan which is slideable in suitable guideways 23 mounted on the side walls of the refrigerator cabinet. The drip pan is slightly larger in its overall horizontal dimensions than the horizontal dimensions of the evaporator 13. The front edge of the drip pan normally is located relatively closely adjacent to the closure 16a and below the upper edge thereof. The drip pan may be removed from the position shown in Figure 2 and rested upon the shelf 14 in the manner shown in Figure 3.

The closures 16 and 16a are provided with suitable handles 18 and 19 by means of which the closures may be swung from their closed positions shown in the drawings to their open

positions whereby to permit access to the evaporator and to the space between the evaporator and the shelf 14. The handle 18 for the closure 16 may be of any suitable form but preferably is a plastic member of double channel shape extending the full width of the closure 16.

The handle 19 for the closure 16a is an elongated member formed to the cross-section shown in Figures 2 and 3. As can be seen in those figures, the handle has a top portion 20 which inclines downwardly and rearwardly and extends a substantial distance both in front and in rear of the closure. A depending flange 21, which may be suitably ornamented, provides means by which the operator may grip the handle when it is desired to open or close the closure. Intermediate the front and rear edges of the inclined top portion 20 are flanges 21a. The flanges 21a are designed to grip the upper edge of the closure 16a and thereby hold the handle on the closure. The rear edge of the top portion 20 is curved downwardly, as at 22.

An inspection of the drawings, particularly Figures 2 and 3, will show that the rear edge of the top portion 20 of the handle 19 overhangs the front edge of the drip pan 17 when the latter is placed in the guideway 22, as in Figure 2, or when it rests upon the shelf 14, as in Figure 3. Thus, any moisture condensing upon the closure 16 or forming by the melting of frost which has been deposited upon the closure 16, and dripping therefrom, will strike the top of the handle 19 and be deflected rearwardly sufficiently to fall into the drip pan 17. There is no possibility of such moisture running down upon the closure 16a and dripping into the lower part of the refrigerator or falling through the gap between the front of the drip pan 17 and the closure 16a.

Not only does the handle 19 prevent moisture from falling into the lower portion of the refrigerator, but it serves to conceal the gap formed between the evaporator 13 and the drip pan 17 when the latter is in its upper position, as shown in Figure 2. The latter function adds to the appearance of the refrigerator as a whole.

45

The handle is relatively simple and inexpensive to manufacture, as it can be made of molded plastic or of extruded metal, such as aluminum.

The scope of the invention is indicated in the appended claims.

I claim:

1. A refrigerator comprising a cabinet having a food storage chamber therein provided with a main closure, an evaporator in the chamber for cooling the latter, a first auxiliary closure for said evaporator located at the front thereof and extending in a vertical plane, a second auxiliary closure located below and substantially in the same plane as the first named closure, means below the evaporator in rear of the second auxiliary closure for collecting moisture, and a drip deflector on said second closure at a level above said means and extending rearwardly from said second closure, the rear edge of said drip deflector being located above said means, said drip deflector being provided with means forming a handle for said second closure.

2. A refrigerator comprising a cabinet having a food storage chamber therein provided with a main closure, an evaporator in the chamber for cooling the latter, a first auxiliary closure for said evaporator located at the front thereof and extending in a vertical plane, a second auxiliary closure located below and substantially in the same plane as the first named closure, a drip pan below the evaporator, and a drip deflector on said second closure at a level above said drip pan and extending rearwardly from said second closure, said drip deflector being provided with means forming a handle for said second closure.
